CLAIM

The ornamental design for a resin curing box for cup turner, as shown and described.

DESCRIPTION

FIG. 1 is a perspective view of a resin curing box for cup turner showing our new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a rear, left, bottom perspective view thereof.

FIG. 9 is an enlarged detail view of area 9 shown in FIG. 1; and,

FIG. 10 is an enlarged detail view of area 10 shown in FIG. 8.

The broken lines in the drawings depict portions of the resin curing box for cup turner that form no part of the claimed design.
